No. 701,368.

Patented June 3, 1902.

F. E. MILHOLLAND.

LINOTYPE GALLEY.

(Application filed May 20, 1901.)

(No Model.)

UNITED STATES PATENT OFFICE.

FREDERICK EDWIN MILHOLLAND, OF BROOKLYN, NEW YORK.

LINOTYPE-GALLEY.

SPECIFICATION forming part of Letters Patent No. 701,368, dated June 3, 1902

Application filed May 20, 1901. Serial No. 61,081. (No model.)

To all whom it may concern:

Be it known that I, FREDERICK EDWIN MILHOLLAND, a citizen of the United States, and a resident of the city of New York, borough 5 of Brooklyn, in the county of Kings and State of New York, have invented a new and Improved Linotype-Galley, of which the following is a full, clear, and exact description.

The object of the invention is to provide a 10 new and improved galley for conveniently holding any amount of linotype matter up to its full capacity without the aid of quoins, sidesticks, or blocks and which is so constructed that whenever desired the linotype-bars 15 may be readily removed in whole or in part from the galley.

To this end my invention consists of a galley having a removable side and a particular novel clamping mechanism for the holding-ledge, all as particularly described and claimed hereinafter.

Reference is to be had to the accompanying drawings, forming a part of this specification, in which similar characters of reference indicate corresponding parts in all the views.

Figure 1 is a perspective view of my improved galley in a locked position. Fig. 2 is a similar view of the galley with the clamp removed and the side bar raised, and Fig. 3 30 is a partial plan of my improvement.

The improved galley is provided with a bottom A, a side B, and two ends C and D. These parts are rigidly connected with each other. The fourth side of the box or galley is open 35 and is adapted to receive the removable side bar E, which is provided at its ends with projections E' and vertical sockets E'', which are adapted to receive pins C'' D', provided on the projecting lower portions of the end walls 40 C and D. The side bar E is also provided at a suitable point—for instance, at the center—with a recess E''' to facilitate taking hold of said side for the purpose of removing it or again inserting it. It will be understood that 45 the type in the linotype-bars are first placed against the upper end C of the galley. The lowermost bar is engaged by a jaw F, which is provided at its end adjacent to the side B with a dovetailed portion F', which is adapt- 50 ed to slide in a longitudinal slideway B', extending lengthwise of the side B on the inner surface thereof. It will be understood

that the jaw F is substantially L-shaped, its transverse member engaging the last linotype-bar, while its short longitudinal member has 55 the dovetailed portion F', above referred to. In order to lock the jaw F in any desired position, I provide a clamping-lever G, which is fulcrumed to turn about a horizontal axis G' in a lug G'', projected inwardly from the 60 face F'' of the dovetailed portion F' and integral therewith. The said lever G is provided at one of its ends with eccentric cams G'', integral therewith and arranged to engage the lower inner surface of the side B, adjacent 65 to the slideway B', in such a manner that when the lever G is thrown down the cam G'' will draw the dovetailed portion F' a slight distance toward the center of the galley, thus causing it to bind against the internal walls 70 of the slideway B', and thus lock the jaw F against movement lengthwise of the galley—that is to say, the dovetailed portion F' is locked in position by the cams pulling upon the lug where it extends through the slot. It 75 will be understood that the free end of the jaw F, adjacent to the removable side D, has no engagement with said side, or at least is not pressed against said side at the time the ledge is clamped by means of the lever G. 80 No strain, therefore, ever comes on the removable side E, and it cannot bulge and is always readily removable.

It will be understood that the galley is filled in the usual way, the jaw F holding the type-bars together and being moved toward the lower end D as additional linotype-bars are inserted. When it is desired to correct matter contained in the galley, the side bar E is removed, and the linotype-bars can then be 90 slid out through the open side of the box, either all or singly. In the use of this device, the quoins, sidesticks, and similar appliances are not required to hold the linotype matter in place. The sliding jaw F can be readily 95 locked in any position or quickly unlocked when it is desired to move it by merely lowering or raising the lever G.

Having thus fully described my invention, I claim as new and desire to secure by Letters 100 Patent—

1. A galley having a bottom, and side and end members, and all rigidly secured together, said end members being provided with pins,

and a removable side member provided with apertures for engaging the said pins.

2. A galley provided with an undercut groove, a slideable jaw provided with a dovetailed portion engaging said groove and also provided with a lug, and a lever mounted upon said lug and provided with a cam for engaging a stationary part of the galley, for the purpose of securing said slideable jaw thereto.

3. A galley, comprising a side member provided with an undercut groove, an L-shaped slideable member provided with a dovetailed portion engaging said groove and also provided with a lug, and a lever pivoted upon said lug and provided with cams for engaging a fixed portion of said galley.

4. A galley, comprising a side member provided with an undercut groove, an L-shaped slideable member provided with a dovetailed portion engaging said groove and also provided with a lug, a lever pivoted upon said

lug and provided with cams for engaging a fixed portion of said galley, end members engaging said side member and provided with pins, and a side member provided with holes for engaging said pins.

5. A galley, comprising a side member provided with an undercut groove, an L-shaped slideable member provided with a dovetailed portion engaging said groove, and also provided with a lug, a lever pivoted upon said lug and provided with cams for engaging a fixed portion of said galley, end members fixedly secured to said side member, and a side member removably secured to said end members.

In testimony whereof I have signed my name to this specification in the presence of two subscribing witnesses.

FREDERICK EDWIN MILHOLLAND.
